UNITED STATES PATENT OFFICE.

PHILIP S. JUDY, OF KANSAS CITY, MISSOURI.

METHOD OF MAKING AND MAINTAINING WELLS.

Application filed November 20, 1925. Serial No. 70,310.

My invention relates to a method of making and maintaining wells, and more particularly to water wells of the air lift type, the principal objects of the invention being 5 to effect disposal of material from the water bearing stratum to initially form the well and afterwards maintain its flow; and to support the roof and surrounding stratum in the well hole to provide an adequate flow of 10 pure water over an extended period at a minimum expense of operation and maintenance.

In accomplishing these objects I have provided improved details of structure, the preferred forms of which are illustrated in the accompanying drawings wherein:

Fig. 1 is a vertical section of a well constructed in accordance with my invention and adapted for operation by my improved 20 method.

Fig. 2 is an enlarged view of the upper and lower portions of the same.

Fig. 3 is a cross section on the line 3—3, Fig. 1.

Fig. 4 is a detail, vertical section of the casing, showing an initial step in the making of the well.

Fig. 5 is a similar view, showing the tubing in place.

Fig. 6 is a similar view showing the excavating and water flow elements and gravel in place in the casing preparatory to making the water bed.

Fig. 7 is a similar view, showing the water bed partially formed.

Referring more in detail to the drawings:

I designates a well hole sunk through a soil formation 2 including strata of different 40 characteristics, into a water bearing sand and gravel stratum 3 lying above a bed rock 4.

Extending through the well hole and, initially, to the bed rock is a casing 5 constituting a wall for the well hole, whereby the hole is maintained and cavings of loose stratum held back during the making period and afterwards during the operation and cleaning of the well.

Extending through the casing 5 is a tubing 6 of substantially less diameter than the casing and of greater length, so that it may be extended through the bed rock to a substantial depth below the water stratum, the 55 tubing having a perforated section 7 at such distance above its lower end as to be located

within the water stratum and extended a short distance into the bed rock, the upper end of the tubing being also extended above the top of the casing. Extending through 60 the tubing 6 is a pipe 8 which terminates slightly above the bottom of the tubing and is extended a short distance thereabove where it carries a valve 9, having a laterally extending stem 10 provided with a hand wheel 11, the pipe 8 being adapted for the delivery of water from the well to the surface, and for cleaning the well as will be hereinafter described. Also extending through the tubing 6 is an air pipe 12 having 70 an elbow 13 at its lower end comprising a nozzle 14 that is located within the lower end of the pipe 8, the air pipe being also extended above the tubing and turned laterally for connection with a compressor or other pressure medium supply (not shown), the air pipe having a control valve 15 at an easily accessible point in its laterally turned portion.

The parts just described form permanent 80 elements of the well and are those initially installed for the making of the well.

After the well is made, as will presently be described, a head 16 is formed about the upper portions of the tubular members to 85 permanently embed them, the head being preferably formed of concrete and comprising an inclined chute channel 17 leading to the casing 5 and having a door 18 at the side of the head, through which gravel may be 90 delivered to the casing.

The head 16 is located in a pit 19 to give it a permanent foundation, and rises to any desired height above the surface of the ground, the upper portion being chambered 95 to house the projecting ends of the water and air pipes with their valves and appurtenances, and having windows 20 in its side walls through which operation of the well may be observed, and a manhole 21 in its top, through which access may be had to the chamber 22 upon the removal of a cover 23.

The valve stem 10 controlling flow through the water pipe 8 preferably extends through a bearing 24 in one of the side walls of the well head so that the hand wheel 11 may be operated from the exterior of the well head. The valve housing is extended upwardly to provide a neck 26, and mounted on said neck is an umbrella 27 of any well known type, into which water is delivered 105 from the pipe 8 to spray and cascade within 110

the well head chamber, thereby aerating the water and providing for easy observation of its volume.

A well seal 28 is located on the bottom of 5 the chamber 22 to cover the tubing 6 and hold the pipes 8 and 12 in proper relation.

Opening to the bottom of the chamber 22 is a pipe 29 which may lead to any suitable storage reservoir.

10 In making the well the casing 5 is lowered to bed rock (Fig. 4). The tube 6 is then extended through the casing and through the bed rock to a substantial depth below the water stratum in order to form a pit 15 within which water may accumulate, the tubing having its coarsely perforated section located within the water stratum and extended downwardly a short distance into the bed rock, (Fig. 5).

20 With the casing and tubing in place the water and air pipes are lowered through the tubing and a supply of screened gravel located within the casing about the tubing (Fig. 6). Air is then let into the air pipe to 25 discharge upwardly into the water pipe, and the casing 5 is jacked up slightly to form an opening above the bed rock. Water flowing from the stratum through the opening beneath the casing and through the apertures in the tubing will descend about the water pipe to the open lower end of the pipe and then travel upwardly under force 30 of the air lift to discharge at the surface. Some of the fine material of the stratum and from around the mouth of the well hole at the top of the bed rock will be carried along with the water, making an excavation in the stratum about the tubing beneath the casing into which the gravel will flow by 35 gravity to form a water bed.

40 The casing is further jacked up by degrees, the excavation is enlarged, and gravel flowed into the excavation until a bed of desired proportions is made, the valve on the tubing being occasionally closed and water backflowed into the stratum to loosen the material so that it can be drawn out when the upward flow is again resumed, the air pressure being sufficient to force the gravel 45 into the stratum and grind the material loose so that it can pass through the gravel bed upon resumption of the upward flow through the water pipe. When the bed is sufficiently large, the elevation of the casing 50 is discontinued, the pump head formed about the top of the casing and the well completed, as illustrated in Fig. 2.

55 Water then continues to flow from the stratum and through the gravel water bed into the tubing, and is exhausted in the tubing by the air lift for discharge from the top of the tubing into the umbrella where it is sprayed and cascaded, eventually flowing 60 through the outlet pipe to the storage reservoir.

After the well has been in operation for some time, fine material from the porous stratum will accumulate in the gravel bed and interfere with free flow of water to the tubing. When this occurs, the valve at the top of the tubing may be closed to shut off the outlet, and air, continuing to blow into the water pipe, will cause backflow of water through the tubing, out through the apertures into the gravel bed and out through the gravel bed into the porous stratum, washing the gravel free of its accumulations and further loosening the water stratum. When the valve is again open, this loosened material flows through the gravel bed into the tubing and is delivered at the top of the well with the water, the volume of flow thereby being restored and increased because of the enlargement of the excavation.

65 As the excavation is enlarged by this back flow and the removal of the fine material with the water, more gravel is delivered from the casing to compensate for the removed material, thereby at all times maintaining a sufficient gravel bed for supporting the walls and roof of the excavation. This cleaning operation may be repeated from time to time as it may become necessary to maintain a proper flow from the well.

70 What I claim and desire to secure by Letters Patent is:—

75 1. The method of making and maintaining wells consisting of locating a perforated tube in a well, delivering gravel to a water stratum about the perforated tube to form a porous water bed about the perforated tube, drawing water and fine material from the stratum through the bed and delivering the same to the surface through the tube by induced upward flow in the tube, and intermittently backflowing contents of the tube through the bed to loosen accumulation in the bed.

80 2. The method of making and maintaining wells consisting of locating a perforated tube in a well, delivering gravel to a water stratum about the perforated tube to form a porous water bed about the perforated tube, drawing water and fine material from the stratum through the bed and delivering the same to the surface through the tube by induced upward flow in the tube, intermittently backflowing contents of the tube through the bed to loosen accumulation in the bed 85 and supplying fresh gravel to compensate for fine material removed from the well.

85 3. The method of making and maintaining wells, consisting of delivering gravel to a water stratum about a perforated tube to form a porous water bed, exhausting contents of the tube through a contained pipe to draw fine material and water from the stratum to clear the bed, and intermittently closing off the pipe and exerting back pressure on contents of the tube to backflow 90

such contents through the bed to clear the bed.

4. The method of making and maintaining wells, consisting of confining gravel about a perforated tube within a water stratum, exhausting contents of the tube to excavate about the tube, raising the gravel confining element to permit flow of gravel into the excavation to form a water bed, con-

tinuing to exhaust contents of the tube to draw water and fine material through the gravel to clear and expand the bed, intermittently backflowing contents of the tube through the gravel to clear the bed, and supplying gravel to compensate for material removed from the stratum. 15

In testimony whereof I affix my signature:
PHILIP S. JUDY.
